FLASH LIGHT

Herman G. Graubner, Lakewood, and Albert G. Saurwein, Cleveland, Ohio, assignors to National Carbon Company, Inc., a corporation of New York

Application May 25, 1931, Serial No. 539,894

16 Claims. (Cl. 200—60)

The invention is a new electric switch for a flashlight and a new means for mounting a co-operating insulated conductor of electricity on the metal casing thereof.

5 One object is to provide a switch having four operative positions, comprising: neutral, in which the switch is latched in open circuit position; locked, in which the switch is locked in open circuit position; flash, in which the switch is 10 manually held in closed circuit position; and steady, in which the switch is locked in closed circuit position.

Another object is to provide a switch having an operating button that is protected or shielded 15 in all open circuit positions against accidental movement to closed circuit position, and when in locked position is doubly protected against accidental movement to closed circuit position.

Still other objects are to provide a switch having a minimum number of rugged parts, and to provide simpler and stronger means for mounting the insulated conductor that cooperates with the switch. Other aims, objects, and novel features, are disclosed by the following specification 25 and the accompanying illustrations, in which:

Fig. 1 is a top view of our switch mounted on a metal flashlight casing of which only a fragment is shown;

Fig. 2 is a section of the switch and the upper 30 wall of the casing taken along line 2—2 of Fig. 1 showing the switch in neutral position;

Fig. 3 is a similar section showing the switch in locked position;

Fig. 4 is a similar section showing the switch 35 in flash position;

Fig. 5 is a similar section showing the switch in steady position;

Fig. 6 is a fragmentary view of the top of the 40 casing with the switch removed to show the position of the conductor; and,

Fig. 7 is a sectional view along line 7—7 of Fig. 6, showing the means for mounting the conductor.

The casing of the flashlight is preferably a 45 cylindrical tube of sheet metal having threads or other means at each end thereof by which it is joined to other portions of the flashlight. The conductor is preferably a strip of sheet metal having an intimate unbroken coating of dielectric material formed therearound. This conductor is 50 firmly clamped to the inner wall of the casing by two or more ears sheared from the wall thereof and turned inward over the edge of the conductor. The rear end of the conductor extends outward through a lateral opening in the wall of the casing and, preferably, lies either against or close

to the outside thereof. A portion of the outer surface of this part of the conductor has the dielectric removed therefrom so that the metal surface thereof is exposed.

The switch is preferably mounted on the outside of the casing over the exposed portion of the conductor with which it makes contact when in closed circuit position to close the electric circuit through the battery, bulb, and other portions of the flashlight which are of a form known to the art and, therefore, not shown for sake of simplicity and clarity.

The casing may be of dielectric material such as fiber, paper, bakelite, or the like, and in such case the conductor may or may not be provided 70 with a covering of insulation according to the requirements of other portions of the flashlight. When a dielectric casing is used the conductor may be attached thereto by a strip of metal in the form of a staple having the ends thereof extending inward through openings in the wall of the casing and turned or bent over the edges of the conductor. While this form of fastening may also be used with a metal casing it is considered preferable to cut the supporting ears 80 from the wall of the casing.

The preferred form of the switch comprises a housing mounted on the outside of the casing by means of rivets or other suitable fastening. The housing is provided with a plurality of slots, and 85 a guide is mounted on the housing by means of overturned ears formed thereon that extend inward through these slots in which they are adapted to slide. This guide is provided with a depression having an opening at the bottom thereof, and a manually depressible switch operating button is held in this opening so that the top thereof is below the top of a raised outer edge of the depression. This raised portion of the guide around the edge or rim of the depression forms 90 a guard that prevents the operating button from being accidentally depressed when the flashlight is placed in contact with any straight or flat surface. The lower end of the button is provided with an outturned flange that rests on the upper surface of the housing; on the under surface of the housing; above an opening in the housing on a spring carried thereby; or on a spring below the opening in the housing, according to which of its operating positions the switch is in.

105 While the preferred form of the switch has four operating positions our invention embraces switches having any combination of two or more of these positions. Furthermore, the raised portion of the guide that prevents the button from 110

being inadvertently depressed may be omitted and the locked position of the switch relied on to prevent it from being accidentally closed.

The structure and operation of the invention will be more quickly and clearly understood by referring to the illustration which shows the preferred form having a conductor 10 provided with an intimate unbroken coating of dielectric 11 held against the inner wall of a tubular metal casing 12 by two or more ears 13 sheared from the wall of the casing and turned inward over the edge of conductor 10 thereby clamping it rigidly in place. The rear end of conductor 10 extends outward through an opening 14 in the wall of casing 12 and is provided with an exposed portion 15 from which the dielectric or insulation 11 has been removed. The casing 12 is also provided with suitable openings 16 for rivets or other means by which the switch is attached. The switch comprises a housing 17 attached to casing 12 over the exposed portion 15 of conductor 10 by a plurality of rivets 18. The central portion of housing 17 is spaced from casing 12 and provided with an elongated opening 19 having a wide or large end and a narrow or small end, and four longitudinally disposed elongated slots 20. A guide 21 is mounted on the upper side of housing 17 and held in place by four ears 22 that extend downward respectively through slots 20, over the edge of which they are turned inward but not crimped tight enough to prevent them from sliding therein. This guide 21 is provided with an opening 23 therein having the under side of the edge or rim thereof spaced above the upper surface of housing 17, and a raised wall 24 around this opening that forms a guard having a function that will be described later.

A button 25 is carried by guide 21 and positioned with respect thereto by the central body thereof which fits loosely in opening 23, and an outturned flange 26 at the lower end thereof that lies between the lower side of the rim of opening 23 and the upper surface of housing 17. A spring 27 is secured to the under side of housing 17 by a rivet 28 and provided with: an upwardly offset portion 29 lying in opening 19 of housing 17 with the upper surface thereof substantially flush with the upper surface of the housing; a downwardly offset or bent portion 30 adapted to make contact with the exposed portion 15 of conductor 10 when this spring is flexed downward; and a portion 31 that extends upward above the upper surface of portion 29 and forms a latch to detain guide 21 and button 25 in either of their open circuit positions.

The relation between the assembled parts is such that when guide 21 is at the limit of its movement in one direction button 25 is supported by the upwardly offset resilient portion 29 of spring 27 directly over the large portion of the elongated opening 19 in housing 17, and when the guide is at the limit of its movement in the other direction the outturned flange 26 of button 25 rests on the rigid surface of housing 17 at or near the edge of the small portion of opening 19. The diameter of flange 26 is small enough to freely pass through the large portion or end of opening 19, and the body of button 25 is small enough to slide into the small end of opening 19 through which flange 26 will not pass.

The button 25, instead of being hollow, may be solid. In that case movement thereof will be restrained by the latch only when moved from neutral position to locked position. However, by

moving the latch nearer the large end of opening 19 it will restrain the movement from locked to neutral position, but not from neutral to locked position. This is a desirable condition as it renders the switch less liable to accidental movement toward closed circuit position and, consequently, the battery less liable to become futilely exhausted.

When the switch is in neutral position, as shown by Figs. 1 and 2, the electric circuit is open and button 25 is supported at normal height in elevated condition by the elevated portion 29 of spring 27 above the large end of opening 19. From this position it may be moved to any one of its three other operative positions.

To place the switch in locked position, as shown in Fig. 3, guide 21 is moved to the left as shown by the drawings, or actually toward the head of the flashlight, without depressing button 25. During this movement latch 31 is depressed by flange 26 of button 25 and this tends to restrain the button in neutral position and prevent accidental movement. When in this position button 25 is in elevated condition and flange 26 is resting on the upper surface of housing 17 at or near the edge of the small end of opening 19. Therefore, button 25 cannot be depressed and, consequently, the circuit is open and the switch is locked. Button 25 is also restrained from movement from this position by latch 31.

In order to move the switch from neutral position to flash position as shown by Fig. 4, button 25 is manually depressed thereby moving flange 26 downward through the large end of opening 19 until the offset portion 30 of spring 27 comes in contact with the exposed portion 15 of conductor 10 thereby closing the electric circuit. When pressure upon button 25 is released, spring 27 moves it back to neutral position.

In order to move the switch from neutral position to steady position, button 25 is manually depressed until the upper surface of rim 26 is below the under surface of housing 17 and then it is moved to the left to the position shown in Fig. 5. In this position the body of button 25 is in the small end of opening 19 and the rim 26 thereof is held against the under side of the housing at or near the edge of opening 19 by spring 27 of which the portion 30 is in contact with the exposed portion 15 of conductor 10. As long as the switch remains in this position the circuit is closed. In order to move the switch back to neutral position guide 21 is simply moved to the right to the large portion of opening 19 where spring 27 moves the button 25 back up to neutral position as shown in Fig. 2.

From the foregoing description it is manifest that our switch may be moved easily from its closed circuit positions to its open circuit positions, but its movement in the opposite direction is accomplished with more difficulty. This tends to prevent accidental closure of the switch and futile exhaustion of the battery. When this switch is in locked position the operating button is held against movement to closed circuit position and also guarded against accidental contact. When the switch is in neutral position the button is likewise guarded. Therefore, although a flashlight equipped with this switch is packed for travel or other purpose without moving the switch to locked position this guard still, to a large extent, prevents the electric circuit from being accidentally closed. Regardless of these safety features, however, our switch may be manually

moved from one position to another without any difficulty whatever.

While we have shown and described only the preferred embodiment of our switch and the support for its cooperating conductor, it is evident that the form and arrangement of the component parts may be varied considerably and still be within the scope of our invention and the interpretation of our claims.

10 We claim:

1. In a flashlight; a metal casing having a slot and a plurality of inturned ears; a sheet metal conductor having an insulated portion held within said casing by said ears and a portion extending outward through said slot and provided with an exposed portion; a switch comprising a housing mounted on said casing over the exposed portion of said conductor and having an elongated opening therein with a large end and a small end; a guide mounted upon said housing and adapted to be moved with respect thereto; a button carried by said guide and provided with an outturned flange at the lower end thereof adapted to occupy a locked position above the small end of said opening, a neutral position above the large end of said opening, a flash position below the large end of said opening, and a steady position below the small end of said opening; and a spring mounted within said housing and provided with: a portion offset upward into said opening and adapted to support said button in said neutral position, a portion offset downward and adapted to be moved into contact with the exposed surface of said conductor by said button when it is moved from neutral to flash position, and to be held in contact therewith while said button is in steady position, and a portion offset upward beyond said first mentioned portion and adapted to detain said button in one or more of said positions.

2. In a flashlight; a metal casing; a conductor having an exposed portion; and a switch comprising a housing mounted on said casing and having an opening therein; a guide mounted upon said housing and adapted to be moved with respect thereto; a button provided with a flange carried by said guide and adapted to cooperate with said opening to occupy: a locked position wherein said flange is over said housing, a neutral position wherein said flange is over said opening, and a flash position wherein said flange is below said opening; and a spring mounted within said housing having a portion offset upward into said opening and adapted to support said button in said neutral position, and a portion adapted to be moved into contact with the exposed portion of said conductor when said button is moved into flash position.

3. In a flashlight; a casing; a conductor having an exposed portion; and a switch comprising a housing mounted on said casing and having an elongated opening therein with a large end and a small end; a guide mounted upon said housing and free to move with respect thereto; a button carried by said guide and provided with a flange above said housing adapted to cooperate with said opening to provide: a neutral position above the large end of said opening, a flash position below the large end of said opening, and a locked position below the small end of said opening; and a spring having a portion in said opening adapted to support said button in said neutral position and a portion to be moved by said button into contact with the exposed portion of said conductor.

4. In a flashlight; a casing; a conductor having an exposed portion; and a switch comprising a housing mounted on said casing and having an elongated opening therein with a small end and a large end; a guide mounted upon said housing and adapted to be moved with respect thereto; a button carried by said guide and provided with an outturned flange above the large end of said opening that is free to move into a locked position above the small end of said opening, a flash position below the large end of said opening, and a steady position below the small end of said opening; and a spring extending into said opening and adapted to support said button in said neutral position and to be held in contact with the exposed portion of said conductor by said button when it is in said flash and steady positions, and means on said spring to detain said button in one or more of said positions.

5. In a flashlight; a metal casing having a slot and a plurality of inturned ears; a sheet metal conductor having an insulated portion held within said casing by said ears and a portion extending outward through said slot and provided with an exposed portion; and a switch mounted on said casing and adapted to make contact with the exposed portion of said conductor to complete the electric circuit of said flashlight.

6. In a flashlight; a switch comprising the combination of an operating button; means for mounting said button to provide two open circuit positions in which said button is in elevated condition, and two closed circuit positions in which said button is in depressed condition; a guard adapted to shield said button from contact with objects liable to accidentally move it to closed circuit position; resilient means for supporting said button in elevated condition in one of said open circuit positions; and rigid means for supporting said button in elevated condition in the other of said open circuit positions, and also for holding said button in depressed condition in one of said closed circuit positions.

7. In a flashlight; a switch comprising the combination of an operating button; means for mounting said button to provide two open circuit positions in which said button is in elevated condition, and two closed circuit positions in which said button is in depressed condition; resilient means for supporting said button in elevated condition in one of said open circuit positions; and stationary means for supporting said button in elevated condition in the other of said open circuit positions, and also for holding said button in depressed condition in one of said closed circuit positions.

8. In a flashlight; a switch comprising a housing mounted on a casing over the exposed portion of a conductor and having an elongated opening therein with a large end and a small end; a guide mounted upon said housing and adapted to be moved with respect thereto; a button carried by said guide and provided with an outturned flange at the lower end thereof adapted to occupy a locked position above the small end of said opening, a neutral position below the large end of said opening, a flash position below the large end of said opening, and a steady position below the small end of said opening; and a spring mounted within said housing and provided with: a portion offset upward into said opening and adapted to support said button in said neutral position, a portion offset downward and adapted to be moved into contact with the exposed surface of said conductor by said button when it is moved from neu-

- tral to flash position, and to be held in contact therewith while said button is in steady position, and a portion offset upward beyond said first mentioned portion and adapted to detain said button in one or more of said positions. 5
9. In a flashlight; a switch comprising a housing mounted on a casing and having an opening therein; a guide mounted upon said housing and adapted to be moved with respect thereto; a button provided with a flange carried by said guide and adapted to cooperate with said opening to occupy: a locked position wherein said flange is over said housing, a neutral position wherein said flange is over said opening, and a flash position wherein said flange is below said opening; and a spring mounted within said housing having a portion offset upward into said opening and adapted to support said button in said neutral position, and a portion adapted to be moved into contact with the exposed portion of a conductor when said button is moved into flash position. 10
10. In a flashlight; a switch comprising a housing mounted on a casing and having an elongated opening therein with a small end and a large end; a guide mounted upon said housing and free to move with respect thereto; a button carried by said guide and provided with an outturned flange adapted to cooperate with said opening to provide: a neutral position above said housing at the large end of said opening, a locked position above said housing at the small end of said opening, a flash position below said housing at the large end of said opening, and a steady position below said housing at the small end of said opening; and a spring having a portion in said opening adapted to support said button in said neutral position, a portion adapted to be held in contact with the exposed portion of said conductor by said button when it is in said flash and steady positions, and a portion above said opening to detain said button in one or more of said positions. 15
11. In a flashlight; a metal casing having a slot and a plurality of inturned ears; a sheet metal conductor having an insulated portion held within said casing by said ears and a portion extending outward through said slot and provided with an exposed portion. 20
12. In a flashlight, a switch comprising an operating button having a flange; means comprising a sliding guide for mounting said button to provide independent vertical and conjoint horizontal movement into two open and two closed circuit positions; resilient means for moving said button from one of said closed circuit positions to one of said open circuit positions; and stationary means cooperating with said flange and said guide to provide a path in which said but- 25
- ton is free to move to one of said open circuit positions only from the other of said open circuit positions, and to one of said closed circuit positions only from the other of said closed circuit positions. 30
13. In a flashlight, a switch comprising an operating button; means for mounting said button to provide a path of movement having two open and two closed circuit positions in series; a resilient circuit closing contact operable by said button; and means on said contact to resist movement of said button from one of the other of said open circuit positions, and from one to the other of said closed circuit positions. 35
14. In a flashlight, a switch comprising a housing having a wall with an elongated opening therein having a large end, and a small end; a guide mounted on said housing and free to move along said opening; a button carried by said guide and provided with a flange above said wall smaller than the large end and larger than the small end of said opening; and a spring secured to said housing having a portion substantially flush with the upper surface of said wall. 40
15. In a flashlight, a switch comprising a housing having a wall with an elongated opening therein having a rim and a narrow end; a spring having a portion in said opening substantially flush with the upper surface of said wall; a guide mounted on said housing and free to move along said opening; and an operating button having a flange mounted in said guide above said wall and free to move through said opening with said spring, and also free to move with said guide along said rim either inside or outside of said housing. 45
16. In a flashlight, a switch comprising a housing having a wall with an elongated opening therein having a wide end and a narrow end; a depressible operating button having a flange smaller than the large end of said opening and free to move therethrough; means for mounting said button on said housing comprising a guide free to move along said opening with said button; means for supporting said button in neutral position above said wall comprising a spring secured to said housing with a portion in said opening substantially flush with the upper surface of said wall; means comprising said flange and a portion of said wall at the narrow end of said opening for maintaining said button in open circuit position with said flange above said wall and in closed circuit position with said flange below said wall; and means movable by said button for closing a circuit when said flange is below said wall. 50
